UNITED STATES PATENT OFFICE.

CHARLES M. DUMOND, OF CEDAR FALLS, IOWA.

ACTUATING MECHANISM FOR WASHING-MACHINES.

1,139,404.

Specification of Letters Patent. Patented May 11, 1915.

Application filed July 31, 1913. Serial No. 783,801.

To all whom it may concern:

Be it known that I, CHARLES M. DUMOND, a citizen of the United States of America, and a resident of Cedar Falls, Blackhawk county, Iowa, have invented certain new and useful Improvements in Actuating Mechanism for Washing-Machines, of which the following is a specification.

My invention relates to improvements in actuating mechanism for washing-machines and the like, and the object of my improvement is to furnish easily driven anti-friction driving mechanism adapted to impart simultaneous reciprocatory and rocking movements to a shaft or plunger-rod, such as is used in washing-machines to operate a plunger.

This object I have accomplished by the mechanism which is hereinafter described and claimed, and which is illustrated in the accompanying drawings, in which:

Figure 1 is an elevation of a part of the mechanism of my said invention, as operatively connected to the plunger-rod of a washing-machine, a portion of the washing-machine top being shown in vertical central transverse section. Fig. 2 is a side elevation of said actuating mechanism with parts thereof broken away. Fig. 3 is a detail perspective view of the rocking fork and its connected crank-arm. Fig. 4 is an enlarged detail of a part of the plunger-rod and the flanged sleeve thereon, the flanges of the latter being transversely vertically sectioned in order to display the roller bearings therein. Fig. 5 is a horizontal section of said plunger-rod, showing said flange carrying sleeve in plan as secured thereon. Fig. 6 is an upper plan view of the rocking fork, showing its operative connections to the crank-arm, and to the flange carrying sleeve on the plunger-rod.

Similar numerals of reference denote corresponding parts throughout the several views.

My invention herein is an improvement upon my previous invention of actuating-means for washing-machines, application for which, Serial No. 715,434 was filed on August 16, 1912, in the United States Patent Office.

The numeral 1 denotes a vertical cylindrical plunger-rod seated in vertically spaced bearings in a supporting frame 9 secured on the top 12 of a washing-machine tub 11, said rod carrying upon its lower end a depend-

ing fixed conical hollow head or plunger 10, the latter adapted to act upon the contents of the tub in a well known manner when said rod is simultaneously vertically reciprocated and horizontally rocked in opposite directions.

My invention pertains to the means which I have adopted for producing these simultaneous movements of said plunger-rod.

Said means comprise the following described mechanism: Upon the top 12 is secured another supporting frame 15, comprising a pair of fixed uprights or standards, spaced apart from each other in a radial direction from said plunger rod. Upon the tops of said standards are alined horizontal bearings adapted to receive a rotary shaft 14, on whose outer end is secured a fly-wheel 13, provided with a crank handle. On the opposite end of said shaft 14 is secured a crank-arm 16, whose outer extremity is transversely orificed to receive movably the stem 8 of another fork 4 is swiveled between the members of the fork 7 on a pintle 6. A sleeve 18 is secured adjustably upon said plunger-rod 1 by means of a set-screw 3, secured to its upper part 2. This sleeve has integral vertically spaced horizontal flanges 5 on opposite sides thereof, as is particularly indicated in Figs. 4 to 6 inclusive. The upper surface of the lower flange of said sleeve has small cylindrical sockets near its ends alined vertically with cylindrical orifices above in the upper flange, said orifices and sockets being adapted to receive rotatably the anti-friction rollers 17, the rollers being introduced from above so as to be easily withdrawn, if desired. The members of the fork 4 are slidably seated horizontally upon and embrace said oppositely placed anti-friction rolls 17 so as to contact slidably therewith.

The operation of said actuating-means is as follows: When rotation is imparted to the shaft 14 by means of the use of a crank-handle of the fly-wheel 13 or by other means, and the crank 16 is also rotated, the swivel connection at 6 and 7 of the fork 4 with said crank 16 is likewise rotated and carried around with the crank, but since the members of the fork 4 are engaged between the flanges 5 on the sleeve 2, the fork remains horizontal by carrying said plunger-rod 1 up and down with it. The stem 8 of the fork 4 rocks horizontally while the

crank to which it is connected is rotating. It will be obvious that since the members of the fork 4 are being rocked horizontally simultaneously with the up and down movements, that this simultaneous action will be communicated to said shaft 1, to thereby simultaneously vertically reciprocate and horizontally oscillate the shaft. Since the members of the fork 4 ride contactingly upon and over the spaced anti-friction rollers 17, very little friction is developed between said parts, which renders the action very easy. Since the anti-friction rolls 17 are used in equally spaced pairs on opposite sides of the shaft 1, the members of the fork 4 hold them and said sleeve 18 securely while moving thereover slidably, so that there is no danger of displacement of the fork relative to the shaft 1. Since both the pedal 6 in connecting the stem 8 to the fork 6, and the pedal of the fork 7, in its connection to the crank 16 have independent rotary actions, those parts, as well as the anti-friction bearings above described have but little frictional wear, contributing to the ease of the operation of the device.

While I have shown the members of the fork 4 as specifically seated upon anti-friction rollers 17, it is obvious that such rollers may be omitted, if desired, for the purpose of simplicity, and the fork members allowed to slidably engage opposite sides of squared seats on the shaft 1. The action would be the same in both cases, but the former device would be easier to operate. Other or different forms of this device will still come within the scope and principle of my

invention, where substantially the same construction is used.

Having described my invention, what I claim as new, and desire to secure by Letters Patent, is:

1. In combination, a plunger-rod mounted suitably for translatory and rocking movements, a body secured about said rod and having transverse bearings on opposite sides, anti-friction means seated within the bearings in said body, a fork whose members are seated slidably in said bearings upon said anti-friction means, and rotary means so moyably connected to said fork as to cause the latter to impart simultaneous rocking and translatory movements to said plunger-rod.

2. In combination, a plunger-rod mounted suitably for translatory and rocking movements, a body mounted on said rod and having spaced horizontal flanges near each end thereof, anti-friction rollers seated rotatably between said flanges, a fork whose members embrace said rollers between said flanges slidably, the flanges preventing displacement of the fork-members vertically, a rotary crank, and a swivel connection between said crank and said fork adapted to permit the crank to cause the fork to impart simultaneous rocking and translatory movements to said plunger-rod.

Signed at Waterloo, Iowa, this 14th day of July, 1913.

CHARLES M. DUMOND.
